In Germany October 26, 1935**

2 Claims. (Cl. 175—315)

This invention relates to wet electrolytic condensers, and more particularly to electrodes for condensers operating on voltages of the order of 350 volts and more.

Such condensers usually have a container of conductive material acting as the cathode, and an anode whose surface area is made as large as possible to obtain a maximum capacity for a given size container; this surface area, which is provided with an insulating oxide-coating dielectric, determining the capacity of the condenser. To provide the large surface area the anode is formed in various manner, for instance as a helically-wound aluminium strip apertured at various points to permit free passage of the electrolyte, or as a plate of film-forming material bent in the shape of a star. Such constructions, however, have the serious drawback that the paths from the anode through the electrolyte to the cathode-container are different for different points of the anode, which results in the series resistance of the entire condenser being extremely unfavorable.

Although in the so-called "dry" electrolytic condensers having strip electrodes separated by fabric absorbing a pasty electrolyte the paths are the same, such condensers have several disadvantages over wet condensers, including that the oxide film is self-healing to only a very limited extent, and thus after a breakdown the short circuit between the electrodes will remain.

While it has also been suggested to construct an electrolytic condenser with a meander-shaped anode surrounded by a cathode-container equidistantly spaced therefrom, such a construction is mechanically weak and thus subject to variations in series-resistance. Moreover the great danger of short circuit between anode and cathode container as a consequence of the weak construction exists. Although this can be eliminated by supporting the anode and container at a large number of points, such a construction is very complicated, expensive and unsuitable for mass-production.

One object of the present invention is to eliminate the above difficulties and to provide a wet electrolytic condenser which is of simple construction, of large capacity for a given volume, and of low internal resistance.

Another object is to provide a large surface-area electrode which can be inexpensively produced in mass production.

In accordance with the invention, at least one of the electrodes is formed as a plate having a

plurality of concentrically-arranged rings extending perpendicularly thereto.

By making the plate and the rings in one piece, additional supporting means or means for attaching the rings to the plate are unnecessary, whereby a rigid, simple and inexpensive electrode is obtained. Furthermore, such a one-piece electrode, in addition to producing a high capacity for its volume, can be inexpensively manufactured in mass production, for instance in a single extrusion operation.

In one embodiment of the invention both electrodes are provided with extending rings uniformly spaced apart and so arranged that the rings of the electrodes telescope. In this manner a small and uniform distance between the surfaces of the electrodes, and a constant and possibly lower series resistance are obtained, whereby the operation of the condenser is very favorable.

In another embodiment only one electrode, preferably the anode, is provided with projecting rings, and these rings are diametrically slotted to decrease the series-resistance.

Further advantages and features of the invention will appear as the description progresses.

In order that the invention may be clearly understood and readily carried into effect, it will be described in more detail with reference to the accompanying drawing, in which:

Fig. 1 is a sectional view of a condenser having a large surface electrode according to the prior art;

Fig. 2 is a sectionized side view of a condenser according to the invention;

Fig. 3 is a sectionized side view of a condenser according to another embodiment of the invention;

Fig. 4 is a sectional view taken along lines 4—4 of Fig. 3.

The disadvantages of using electrodes spaced apart at unequal distances will be explained in more detail in connection with Fig. 1, in which an anode 31 having a star-shaped section 31, is disposed within a cylindrical cathode-container 34.

As the distances between the anode 31 and the cathode-container 34 are not the same throughout, the "partial capacities," i. e., the capacities from which the total capacity of the condenser unit is built up, have different resistances in series which, in an unfavorable construction may be fairly large. For example, consider a condenser having a total capacity of 18 mfd., and an electrolyte having a specific resistance of about 55

- 10,000 ohms per cubic centimeter at 20° C., intended to operate on 500 volts, 50° C., and consider another electrolyte with specific resistance of about 15,000 to 20,000 ohms per cubic centimeter at 20° C., intended to operate on 550 volts, 50° C. Such a condenser may have a "partial capacity" corresponding to 6 mfd. as supplied by a surface area of about 100 square centimeters lying at a distance of 2 cm. from the cathode—
 10 which may readily occur in the usual constructions of wet electrolytic condensers. With a specific resistance of the electrolyte of 15,000 ohms per cubic centimeter the resistance in series with the 6 mfd. will amount to

15

$$15,000 \times \frac{2}{100} = 300 \text{ ohms}$$

This means a very high power factor loss, since the impedance of 6 mfd. at 100 cycles will amount to about 260 ohms.

Below are the calculations for a theoretical case in which the total capacity of the condenser is 18 mfd., (real value as would be measured by ballistic methods) and in which the distances between the anode and cathode of the parallel-connected "partial capacities" have such values that the partial capacities are in series with the following resistances:

30

I

	Partial capacities	Resistances at 20° C.
35	2 Microfarads	100
	4 Microfarads	200
	6 Microfarads	400
	6 Microfarads	800

40 A condenser having the above partial capacities and resistances in series will have the following total capacities and total series resistances depending upon the frequency used:

45

II

	Frequency	Total capacity	Total series resistance
50	50 cycles	Microfarads	Ohms
	100 cycles	16.8	131
	500 cycles	7.7	103

From Table II it appears that, due to the greatly varying series resistance and also to its high value, 55 5 of the 18 mfd. are lost at 100 cycles, and that, as the frequency increases, the capacity loss is further increased.

Another difficulty caused by the unequal spacing of the cathode and the anode is the high degree to which the capacity and the series-resistance are dependent upon temperature, due to large changes in the specific resistance of the electrolyte with temperature. Although this does 65 not apply to such an extent to aqueous electrolytes, it does apply to high-voltage condensers in which an electrolyte in a glycerol solution is preferably used.

This temperature dependency of the electrolyte 70 is so great that at about 45° C. for instance, the specific resistance of the electrolyte is $\frac{1}{4}$ the resistance at 20° C. Thus, when the values of Table I are calculated at 45° C., all of the series resistances will be reduced to one-quarter as follows:

III

Partial capacities	Resistances at 45° C.
2 microfarads	25
4 microfarads	50
6 microfarads	100
6 microfarads	200

With the partial resistances of Table III, the condenser would have the following total capacities and total resistances at the given frequencies:

IV

Frequencies	Total capacity	Total resistance
50 cycles	Microfarads	Ohms
100 cycles	17.4	36
500 cycles	17.0	34
	12.2	24

Comparison of Tables II and IV clearly brings out the high temperature dependency of the series resistance and of the capacity.

From the above it clearly appears that it is of great importance in an electrolytic condenser to make the series-resistance between every point of the formed electrode and the counter-electrode as equal and as small as possible.

In the embodiment of the invention illustrated in Fig. 2 the condenser comprises a positive electrode 1, a negative electrode 9, and a liquid electrolyte 30 for example a mixture of 200 gr. boric acid (H_3BO_3), 1000 gr. glycerol, and 110 cc. ammonia (NH_4OH) 10% by weight. The electrode 1 comprises a plate portion 31 and a plurality of projecting concentric rings 32, and is provided with an insulating oxide coating. The electrodes are preferably made of a film-forming metal such as aluminum, which can be extruded into a one-piece body, and their active surfaces may be etched to increase the capacity.

The electrode 1 is secured to a base 4 of insulating material, for instance a moldable material containing synthetic resin, by means of a metal pin 2 extending through a central bore in the plate portion 31 and base 4. The pin 2 has a flanged upper end 33 bearing upon the upper surface of plate 31, whereas its lower end is riveted over the base 4 with the interposition of a terminal 7. The base 4 is provided with an externally-threaded projecting portion 5 for mounting the condenser, and a gasket 3, for instance of rubber, is disposed between the base 4 and circular corrugations on the adjacent surface of plate 31 to form a liquid-tight seal.

A cup-shaped member 34, whose closed end surface forms a dome 20 provided with one or more apertures 22, has its lower edge bent over the edge of the base 4 with the interposition of gasket 3 to effect a liquid-tight seal. Secured to the member 14 by means of a ring-shaped indentation, formed by rolling, is the electrode 9, which is similar to electrode 1 and is provided with a plurality of ring-shaped projections 11 spaced so as to telescope with the rings 32 of electrode 1.

Electrode 9 is provided with a plurality of bores 19 to allow the electrolyte 30 to flow into the space formed between the rings 32 and 11, and with a central counterbore into which is secured the top of a porcelain tube 10 extending with a snug fit into the space formed by the inner ring 32. A gasket 8, for instance of rubber, is disposed between the top of pin 2 and the bot-

tom of tube 10, whereas a gasket 14 extends between member 9 and the top inner ring 32 and partly within the spaces 15.

In assembling the condenser the member 9 with tube 10 secured thereto is pressed down so as to compress the gasket 8, which prevents the electrolyte from reaching the top of pin 2 and passing between pin 2 and base 1; thus preventing corrosion of pin 2. If pin 2 is of a material which does not form an oxide layer, gasket 8 also serves to prevent short-circuiting between the electrodes through the electrolyte. The gasket 14 serves to space the electrodes 1 and 9 at the correct distance and also to prevent the electrolyte 30 contained in space 15 from creeping upward along tube 10. The electrodes 1 and 9 are telescoped to such an extent that the distance between the ends of rings 11 and the surface 12 of plate 31 is substantially equal to the distance 13 between adjacent surfaces of rings 32 and 11.

Bearing upon the top of the dome 20 and secured to member 34 by a rolled indentation at 36 is a cup-shaped cover 23 provided with a vent hole 25. Surrounding the dome 20 so as to cover the apertures 22 is a band of flexible material, for instance rubber, which in known manner serves to vent the gases developed during the operation of the condenser. It will be noted that by forming a dome 20 on the member 34 and locating the vent holes 22 therein, these holes are located well above the surface of the electrolyte 30, thereby minimizing the possibility of the electrolyte being carried out with the escaping vent gases.

To completely prevent the escape of electrolyte with the venting gases, and thus to prevent corrosion of objects mounted in the vicinity of the condenser, the space formed between the members 23 and 16 is filled with a suitable liquid-absorbing material 23 such as sawdust, whereby only the gases will escape through the aperture 25.

The condenser shown in Figs. 3 and 4 has in general a construction similar to that of Fig. 3 with the exception that only the anode is shaped according to the invention; the container itself 45 acting as the cathode. In the construction shown in Figs. 3 and 4 the anode 51 is similar to that of electrode 1 with the exception that the rings 52 are provided with a plurality of, preferably about 10 to 15, diametrical slots 53 (see Fig. 4), which 50 may be saw cuts. The slots 53 serve to reduce the series resistance and by giving them a width less than the thickness of the rings 52, the active

surface and thus the capacity of the electrode is increased, whereas the series resistance retains a suitable value. An electrolytic condenser with an anode according to the invention with five concentric rings of utmost diameter of 24 mm. and a height of 55 mm., surface of the anode 275 square centimeters, has for 320 volt a capacity of 32 mfd. and a series resistance of only 10 ohms. This latter value may be reduced to 5 ohms by mounting in the center of the container a metal bar fixed to the container thus serving as an inner cathode-container. The series-resistance for a condenser of similar electric properties but with an anode as drawn in Fig. 1 is about 15 ohms or more.

While we have described our invention in connection with specific examples and constructions, we do not wish to be limited thereto, but desire the appended claims to be construed as broadly as permissible in view of the prior art.

What we claim is:

1. An electrolytic condenser comprising a liquid electrolyte, two electrodes each consisting of a one-piece body having a plate-shaped bottom portion and a plurality of concentric ring-shaped portions extending perpendicularly to said bottom portion, said bodies being arranged with the ring-shaped portions interlapping with their opposing surfaces equidistantly spaced apart and parallel, the ring-shaped portions of one electrode 25 alternating with the ring-shaped portions of the other electrode.

2. An electrolytic condenser comprising a liquid electrolyte, a container, an electrode having a bottom portion and a plurality of concentric rings 35 extending perpendicularly to said portion, a second electrode having a bottom portion, and a plurality of rings extending perpendicularly to said portion and telescoping with the rings of said first electrode, means to insulate said electrodes 40 from each other and to space said rings apart, said means comprising a member of insulating material secured to one electrode and extending within the inner ring of the second electrode, and a gasket of insulating material extending around 45 said member and between said electrodes, said gasket also preventing creepage of the electrolyte along said member.

ANTHONIUS FREDERIK PETER
